(57) **CLAIM**

The ornamental design for a retractable drawer for a robot as shown and described.

DESCRIPTION

FIG. 1 is a front perspective view of embodiment one of the claimed design;
FIG. 2 is a rear perspective view of the embodiment of FIG. 1;
FIG. 3 is a front view of the embodiment of FIG. 1;
FIG. 4 is a rear view of the embodiment of FIG. 1;
FIG. 5 is a side view of the embodiment of FIG. 1;
FIG. 6 is another side view of the embodiment of FIG. 1;
FIG. 7 is a top view of the embodiment of FIG. 1;
FIG. 8 is a bottom view of the embodiment of FIG. 1;
FIG. 9 is a front perspective view of embodiment two of the claimed design;
FIG. 10 is a rear perspective view of the embodiment of FIG. 9;
FIG. 11 is a front view of the embodiment of FIG. 9;
FIG. 12 is a rear view of the embodiment of FIG. 9;
FIG. 13 is a side view of the embodiment of FIG. 9;
FIG. 14 is another side view of the embodiment of FIG. 9;
FIG. 15 is a top view of the embodiment of FIG. 9;
FIG. 16 is a bottom view of the embodiment of FIG. 9;
FIG. 17 is a front perspective view of embodiment three of the claimed design;
FIG. 18 is a rear perspective view of the embodiment of FIG. 17;
FIG. 19 is a front view of the embodiment of FIG. 17;
FIG. 20 is a rear view of the embodiment of FIG. 17;
FIG. 21 is a side view of the embodiment of FIG. 17;
FIG. 22 is another side view of the embodiment of FIG. 17;
FIG. 23 is a top view of the embodiment of FIG. 17;
FIG. 24 is a bottom view of the embodiment of FIG. 17;
FIG. 25 is a front perspective view of embodiment four of the claimed design;
FIG. 26 is a rear perspective view of the embodiment of FIG. 25;
FIG. 27 is a front view of the embodiment of FIG. 25;
FIG. 28 is a rear view of the embodiment of FIG. 25;
FIG. 29 is a side view of the embodiment of FIG. 25;
FIG. 30 is another side view of the embodiment of FIG. 25;
FIG. 31 is a top view of the embodiment of FIG. 25; and,
FIG. 32 is a bottom view of the embodiment of FIG. 25.
